United States Patent Office

Des. 209,019

Patented Oct. 24, 1967

209,019

BOTTLE

Gerald W. Neese, Compton, and John E. Lenhart, Los Angeles, Calif., assignors to Purex Corporation, Ltd., Lakewood, Calif., a corporation of California

Filed July 11, 1966, Ser. No. 3,031

Term of patent 14 years

(Cl. D58—8)

FIG. 1.

FIG. 2.

FIG. 3.

FIG. 4.

FIG. 1 is a view in elevation of a bottle embodying our new design;

FIG. 2 is a plan view thereof;

FIG. 3 is a bottom view thereof; and

FIG. 4 is a fragmentary enlargement of the ribbed portion of the design configuration of FIG. 1.

The dominant features of our design reside in the portions shown in full lines.

We claim:

The ornamental design for a bottle, as shown and described.
